FRATERNAL MEDAL OR SIMILAR ARTICLE

Matthew L. Brown, Springfield, Ohio, assignor to Grand Aerie Fraternal Order of Eagles, Kansas
City, Mo., a corporation of Washington

Application November 27, 1950, Serial No. 13,145

Term of patent 14 years

(Cl. D29—19)

To all whom it may concern:

Be it known that I, Matthew L. Brown, a citizen of the United States, residing at Springfield, county of Clark, and State of Ohio, have invented a new, original, and ornamental Design for a Fraternal Medal or Similar Article, of which the following is a specification, reference being had to the accompanying drawing, forming part thereof.

Figure 1 is a face view of the fraternal medal or similar article embodying my new design; and

The dominant feature of my design resides in the portions shown on the full lines.

I claim:

The ornamental design for a fraternal medal or similar article, substantially as shown and described.

MATTHEW L. BROWN.
